HYDRAULIC BACK GAUGE FOR PAPER CUTTERS

Sydney Frankel, Ridgefield Park, N. J., assignor
to E. P. Lawson Co., Inc., New York, N. Y., a
corporation of New York

Application March 25, 1950, Serial No. 151,936

3 Claims. (Cl. 60—51)

1

My present invention relates to a hydraulically operated back gauge for paper cutters and more particularly to a back gauge operating mechanism adapted to move the back gauge through a series of steps to permit the cutter to perform a series of cuts on a paper stack.

For this purpose in order to obtain speed in operation, the back gauge should move rapidly between cuts. But to ensure that the paper stack will stop at an accurate predetermined cutting position for each cut, the back gauge must be slowed up just before the cutting position so that when it is brought to a stop, the paper stack will not coast beyond the stop position.

The object of my invention, therefore, is the provision of novel hydraulic back gauge operating means which will move the back gauge rapidly between cuts, will slow the back gauge down just before a cutting position is reached and halt the back gauge at the cutting position.

A further object of my invention is the provision of control means for the back gauge of such nature that these operations may be automatically performed.

Another object, to carry out the foregoing objects, is to provide solenoid operated valve elements for the hydraulic operating mechanism so that the foregoing automatic control may be carried out.

Another object is the arrangement of the hydraulic operating means so that, by a shift in valves, it may be reversed to return the back gauge to its initial position.

The foregoing and many other objects of my invention will become apparent from the following description and drawings in which:

Figure 1 is a side view of my novel hydraulically operated back gauge mechanism.

Figure 2 is a rear view of the mechanism of Figure 1.

Figure 3 is a top view of the mechanism of Figure 1 taken from line 3—3 of Figure 2.

Figures 4 to 7 are schematic views of the hydraulic operating mechanism illustrating the operation of the mechanism for fast forward motion (Figure 4), slow forward motion (Figure 5), stopping of the back gauge (Figure 6) and reverse movement of the back gauge (Figure 7).

Referring first to Figures 1 to 3, the cutting machine in connection with which my novel back gauge is used is of the general type shown in Patent No. 2,574,501, issued November 13, 1951, and the back gauge operates for the general purposes therein described.

Thus, the machine is provided with the side 55 pressure from the main relief valve 92 to the

2

frame base casting 200 which carries the bed plate or support 100 for a stack of paper. The back gauge 201 rides on the bed plate 100 and is provided with a bracket 202 extending downwardly through a longitudinal slot in bed plate 100 terminating in a nut 203 which engages the longitudinal screw 204 supported in appropriate bearings 205, 206 at the front and back of the bed plate 100.

10 The front of screw 204 is provided with the hand wheel 210 for manual rotation of screw 204 to obtain manual adjustment of the back gauge 201 when required. Cable 212 extending over guide pulleys 213, 214, 215 is connected to the back gauge 201 and extends up to the indicating and back gauge stop mechanism 220 mounted on the top cross bar 221 of the machine and operating in the manner described in Patent No. 2,628,680, issued February 17, 1953.

15 The side frame members 200 are extended up at 225 to furnish vertical slide ways for a knife bar and clamp which operate in the manner described in Patent No. 2,574,501 issued Nov. 13, 1951. The operating mechanism for the knife bar and clamp are, as described in the aforesaid 20 patents, mounted between the side frame members 225.

25 The feed screw 204 for the back gauge 201 may be rotated for automatic (non-manual) operation by the pulley 11 driven in turn by the hydraulic operating mechanism shown in the figures.

The reservoir tank 81 for the hydraulic fluid used in the system is located rearwardly of the base frame casting 200. An accumulator cylinder 82 is mounted in tank 81 and immersed in the reservoir oil; this obviates the necessity for extended connections between the reservoir 81 and the accumulator cylinder 82.

30 Bracket 84 supported on reservoir tank 81 carries a pump 83 driven by pulley 85 and V-belt 87 from pulley 78 of electric motor 86 mounted on bracket 71 carried by the base casting 200.

35 Pump 83 draws hydraulic fluid from reservoir tank 81 through the pipe 88, filters 89 and 90 and pipe 79 (see Figure 2) and discharges the hydraulic fluid through flexible hose 91 into the main relief valve 92.

40 Main relief valve 92 controls the pressure available to drive the back gauge 201 as hereinafter described. Relief valve 92 may, therefore, be adjusted to any selected pressure; its overflow is discharged through pipe 93 directly back to the reservoir tank 81.

45 Flexible hose 94 conducts hydraulic fluid under pressure from the main relief valve 92 to the

micro-filter 96 and then through pipe 94a to the solenoid valve and sub-base block 95.

Solenoid valve sub-base block 95 is provided with suitable passages hereinafter described in connection with Figures 4 to 7 to establish various hydraulic fluid circuits through the four-way solenoid valve 97 and the two-way solenoid valve 98.

Pipes 99a and 99b connect the solenoid valve sub-base block 95 with the fluid motor 104. The speed and direction of the fluid motor depends on the setting of solenoid valves 97 and 98.

Flexible hose 105 connects the valve sub-base block 95 to pipe 106 which enters the high pressure chamber 73 of accumulator 82. The low pressure chamber 74 of accumulator 82 communicates through opening 75 with the low pressure fluid in reservoir 81.

Piston 76 is urged by compression spring 77 in chamber 74 toward the right with respect to Figure 2 to create an initial elevated pressure in chamber 73 of accumulator 82. Piston 76 thus forms the boundary between chambers 73 and 74.

As pressure in chamber 73 increases, piston 76 is forced to the left against spring 77 further compressing the same. A relief path for excess pressure in chamber 73 is provided by the recess 78 in accumulator 82. When the piston, on being forced to the left with respect to Figure 2, reaches recess 78, the excess fluid under pressure may escape to the low pressure chamber 74 until the spring 77 can move piston 76 back to the right to close the recess 78.

The fluid motor 104 is connected by pulley 60 and belt 61 to pulley 62 on stub shaft 63. Pulley 64 on stub shaft 63 is connected by belt 65 to pulley 11 on screw 204 which drives the back gauge 201.

Thus, the back gauge is driven by the fluid motor 104 which in turn responds to the direction, pressure and rate of flow of the hydraulic fluid as hereinafter described in connection with Figures 4 to 7.

Motor 86 and pump 83 operate constantly so that the direction, pressure and rate of flow of the hydraulic fluid is determined by the valves 97 and 98. Valves 97 and 98 may be operated in any manner; but it is preferred that they be solenoid operated.

In schematic Figures 4 to 7:

I. A diagonally hatched pipe or area indicates that the fluid therein is at atmospheric or reservoir pressure.

II. A horizontally hatched pipe or area indicates that the fluid therein is at the discharge pressure of pump 83.

III. A dotted pipe or area indicates that the fluid therein is at accumulator pressure.

IV. A blank pipe indicates that there is no fluid therein.

For fast operation of the fluid motor 104 in the forward direction to move the back gauge 201 rapidly in the forward direction, the valves 97 and 98 are set in the positions of Figure 4.

In valve 97, port A connected to pipe 105 is connected to port 2 which is connected by passages 119, 127 to valve 98. Port 1 of valve 97 is connected to passage 128 and also to port P1 which is connected to pipe 94a.

Valve 98 is opened to connect passages 119-127 through valve 98 to passages 199a-99a.

The fluid circuit for fluid motor 104 is then from the discharge port of the pump 83 through passage 91 to the main relief valve 92, through passage 94 into the micro-filter 96 and hence

through port 1, through passages 128 and 99b, to the fluid motor 104.

The exhaust of fluid motor 104 is then through passages 99a and 199a to solenoid valve 98 (B1) 5 entering port P2 and leaving port 2', then through passages 127, 119 to port 2 of solenoid valve 97, and out through port A, passage 105 and 106 into pressure chamber 73 of the accumulator 82.

The speed of fluid motor 104 is thus determined by the difference between the pressure in accumulator chamber 73 as maintained by compression spring 77 and the pressure exerted by pump 83.

This difference in pressure is maintained at a constant rate since the reverse relief valve 111 connected by passage 112 to passage 128 and pipe 99b on one side and by passage 110 on the other side to reservoir 81 is biased to maintain passage 112 closed at pump pressure but to connect passages 112 and 110 at pressures substantially above that of pump 83 to prevent too great a back pressure. The relief pressure at valve 111 must be higher, however, than the relief pressure at main relief valve 92 to permit the slow operation of 25 the back gauge 201 hereinbelow described.

In the operation of a back gauge 201, it is necessary to move the back gauge rapidly between cuts, but to slow down the movement of the back gauge as the end of the movement approaches to prevent coasting of the paper stack beyond the cutting point when the back gauge stops.

This slow down of the movement of the back gauge is brought about by closing of the ports 35 P2-2' of the solenoid valve 98 (B1), whereby the only remaining path for the exhaust oil from the fluid motor 104 is through passage 125 and 121 to the restricted orifice 120.

This sudden restriction to oil flow would also 40 build up a high pressure in passage 125 unless said pressure may be relieved through cavitation relief valve 122.

This slows down motor 104 and hence back gauge 201. The excess fluid delivered by the 45 pump 83 which cannot pass through the restricted orifice 120 then discharges through the main relief valve and through pipe 93 into the reservoir 81.

This is the condition shown in Figure 5 where- 50 in all elements are set for forward operation of the back gauge at slow speed.

When the back gauge 201 reaches the stop position (see Figure 6), valve 97 is moved to connect ports P1 and A and to close the other ports 55 and connections.

The fluid motor 104 is thus cut-off and ceases to operate. Pump 83 is then connected by pipes and elements 91, 92, 94, 96, 94a, P1 of 91, A of 97, 105, 106 to the accumulator chamber 73 60 where it may charge up accumulator chamber 73.

After the back gauge 201 has completed its forward movement, it must be returned to its initial retracted position so that it may start over again with a new stack of paper.

65 This is accomplished (as seen in Figure 7) by opening valve 98 and by connecting together ports P1 and 2 of valve 97 and connecting ports 1 and A of valve 97.

The pump 83 will now deliver pressure oil 70 through 91-92-94-96-94a-P1 and 2 of valve 97-119-127-P2 and 2' of valve 98-199a-99a into fluid motor 104.

The function of the "reverse relief valve" is as follows:

75 When the motor is turning in reverse and the

discharge passage is suddenly blocked by the closing of port 1, the momentum of the motor would build up excessive pressure in the passages 99b and 128 and to relieve this condition, the "reverse relief valve" is provided so that oil may be discharged through passage 112 through valve 111 and passage 110 into the reservoir tank 81.

Reverse relief valve 111 permits excess pressure to bleed off from pipe 128 during the reverse operation.

By this means, therefore, a simplified easily controlled hydraulically operated mechanism is provided to permit the fast forward movement, slow forward movement, stopping and reverse movement of back gauge 201.

The restricted orifice member 120 connected by passage 121 across passages 125-99a and 119 combined with the cavitation relief valve 122 in parallel therewith between these passages serve in a manner well-known in the art of hydraulic mechanism to maintain unimpeded operation of the device.

The function of safety valve 124 is as follows:

When the ports 1 and 2 of the valve 97 are closed to stop the fluid motor 104, its momentum will build up pressure in passage 125; said pressure may be relieved through safety valve 124. While cavitation relief valve 122 can open, oil flow therethrough would still be blocked at valve 97, the setting of safety valve 124 being considerably higher than that of valve 122.

By the means herein described, the various movements of the back gauge may be automatically controlled by elements which respond to movement of the back gauge to predetermined positions to slow and then stop the back gauge. Valves 97 and 98 are operated for forward or reverse movement as the case may be.

The valves 97 and 98 may be solenoid operated by means energized in accordance with the disclosure of said Pat. No. 2,628,680 or in any other suitable manner.

In the foregoing I have described my invention solely in connection with specific illustrative embodiments thereof. Since many variations and modifications of my invention will now be obvious to those skilled in the art, I prefer to be bound not by the specific disclosures herein contained but only by the appended claims.

I claim:

1. In a cutting machine having a cutting table, a back gauge movable longitudinally along said cutting table, a longitudinal screw connected to said back gauge for moving the same, and a hydraulic motor adapted to be connected to drive said screw; the invention which comprises a hydraulic system arranged to drive said hydraulic motor; said hydraulic system comprising a reservoir and a container for fluid under pressure and a pump; first multiple valve control means; a connection through said first valve to conduct pressurized fluid from said pump to said hydraulic motor for driving the motor; a second connection from said container for fluid under pressure through said first valve to the opposite side of said motor; said pump delivering fluid to said motor through said first connection at greater pressure than the fluid delivered through said second connection to drive said motor in one direction at a predetermined speed; a second valve in said first connection; said second valve being normally open to maintain said first connection from said pump to said motor; said second valve being operable to divide the flow in said first connection, diverting a portion of said

flow to the reservoir; said last-mentioned operation reducing the pressure in said first connection to a level slightly above that in the second connection and thereby reducing the speed of said hydraulic motor; said first valve being operable to connect said pump directly to said container for fluid under pressure; disconnecting both the container for fluid under pressure and the pump from the hydraulic motor in order to halt said hydraulic motor.

2. In a cutting machine having a cutting table, a back gauge movable longitudinally along said cutting table, a longitudinal screw connected to said back gauge for moving the same, and a hydraulic motor adapted to be connected to drive said screw; the invention which comprises a hydraulic system arranged to drive said hydraulic motor; said hydraulic system comprising a reservoir and a container for fluid under pressure and a pump; first multiple valve control means; a connection through said first valve to conduct pressurized fluid from said pump to said hydraulic motor for driving the motor; a second connection from said container for fluid under pressure through said first valve to the opposite side of said motor; said pump delivering fluid to said motor through said first connection at greater pressure than the fluid delivered through said second connection to drive said motor in one direction at a predetermined speed; a second valve in said first connection; said second valve being normally open to maintain said first connection from said pump to said motor; said second valve being operable to divide the flow in said first connection, diverting a portion of said flow to the reservoir; said last-mentioned operation reducing the pressure in said first connection to a level slightly above that in the second connection and thereby reducing the speed of said hydraulic motor; said first valve being operable to connect said pump directly to said container for fluid under pressure; disconnecting both the container for fluid under pressure and the pump from the hydraulic motor in order to halt said hydraulic motor; said first valve being operable to reverse said first and second connections to cause a reverse movement of said hydraulic motor.

3. In a cutting machine having a cutting table, a back gauge movable longitudinally along said cutting table, a longitudinal screw connected to said back gauge for moving the same, and a hydraulic motor adapted to be connected to drive said screw; the invention which comprises a hydraulic system arranged to drive said hydraulic motor; said hydraulic system comprising a reservoir and a container for fluid under pressure and a pump; first multiple valve control means; a connection through said first valve to conduct pressurized fluid from said pump to said hydraulic motor for driving the motor; a second connection from said container for fluid under pressure through said first valve to the opposite side of said motor; said pump delivering fluid to said motor through said first connection at greater pressure than the fluid delivered through said second connection to drive said motor in one direction at a predetermined speed; a second valve in said first connection; said second valve being normally open to maintain said first connection from said pump to said motor; said second valve being operable to divide the flow in said first connection, diverting a portion of said flow to the reservoir; said last-mentioned operation reducing the pressure in said first connection

tion to a level slightly above that in the second connection and thereby reducing the speed of said hydraulic motor; said first valve being operable to connect said pump directly to said container for fluid under pressure; disconnecting both the container for fluid under pressure and the pump from the hydraulic motor in order to halt said hydraulic motor; said first valve being operable to reverse said first and second connections to cause a reverse movement of said hydraulic motor, solenoid means for operating said first valve.
